L. G. STUBBS Inventor

Attorney

UNITED STATES PATENT OFFICE

LUTHER G. STUBBS, OF HAMLET, NORTH CAROLINA

RADIOCABINET

Application filed February 23, 1932. Serial No. 594,720.

My invention relates to improvements in radio cabinets, and one object of my invention is the provision of a cabinet of the floor or table type which will be provided or equipped with an appliance or attachment providing a smoking set or a desk at the will and desire of the person.

Another object of my invention is the provision of a radio cabinet equipped with a smoking attachment and which will not in the least interfere with the proper functions of the cabinet and which will not detract from the ornamental appearance of the cabinet.

Another object of my invention is the production of a radio cabinet in which will be embodied a set for smoker's use or which can be used as a desk, as may be found desirable and which will not add more than a mere trifle to the cost of the cabinet.

Another object of my invention is the provision of a radio cabinet in which will be embodied an attachment for the use of smokers and which attachment will be normally out of sight, but which can be instantly put in position for use and which will provide a most perfect and complete set for the smoker and dispose the smoker's utensils in the most convenient location.

Another object of my invention is the provision of a radio cabinet in which will be disposed a smoker's set, or a desk, and which by reason of its desirability and usefulness will commend the cabinet to users of a radio.

To attain the objects stated my invention consists of a floor or table radio cabinet provided with an attachment providing a smoker's set or a desk, and further in a radio cabinet embodying novel features of construction and combination of parts, substantially as described and claimed and as shown in the accompanying drawings, in which:

Figure 1 represents a front view of a radio cabinet equipped with my improvements, showing the attachment in position for use.

Figure 2 represents a view taken at right angle to Figure 1, showing the attachment in position for use and showing the smoking set in dotted lines with the parts in the position 50 they assume when in use.

Figure 3 represents a front view of a form of desk cabinet provided with my improvements with the set shown in dotted lines and out of use.

Figure 4 represents a transverse sectional view on an enlarged scale of the important parts of my invention, the use position being in full lines, and the normal position being shown in dotted lines.

Figure 5 represents a vertical sectional view through the complete invention, and

Figure 6 represents a perspective view of the novel form or construction of the swinging member which carries the smoker's articles or necessities.

Figure 7 represents a detail sectional view of a modified construction of my invention serving the two fold function of a smoker's set and a desk.

Referring by numeral to the drawings in which the same numbers of reference are used to denote like parts in all the views:

The numeral 1 designates a cabinet of the floor or console type and 2 designates a cabinet of the character supported on a table or like support and in each type at a suitable and convenient location is a chamber or compartment 3, having a horizontal floor or wall 4.

My attachment or appliance is adapted to normally occupy said chamber 3, and comprises the right angled shaped frame 5, having the curved end walls 6, and hinged at its lower edge 7, to the wall 4, and in this manner the frame may be swung outward and placed in position for use, as shown in full lines in Figure 4, or swung inward out of use as shown in dotted lines in said Figure 4, and the outward movement of the angle shaped frame is limited by the stop 8.

From this construction it will be noted that the angle shaped frame is hinged to swing in and out of the chamber of either a floor or table set and carried by and swingingly or pendantly mounted in said frame is the member which carries the utensils or articles used by the smoker, and which is most clearly shown in Figure 6, and comprises the pair of end portions 9, pivoted at 10, to the end walls of the frame and the

flat horizontal platform portion 11, having a central opening 12, to receive the ash receptacle 13, and at one end with the pair of lugs 14 and the clamping arm 15, to receive and retain the box of matches 16, while at its other end said platform portion is provided with the pair of lugs 17 and the clamping arm of bail 18, for receiving and retaining a box of cigarettes 19, and the front panel 10 or wall of the angle shaped frame is provided with a scratching plate 20, for igniting matches.

It will be noted from Figure 4 that when the frame is lowered the swinging member 15 occupies a vertical position and is retained in a steady place by means of the stop 21, and when desired to use the attachment as a desk the member is raised to the position shown in dotted lines in Figure 4, where it 20 is held out of the way by means of a suitable spring catch 22, carried by one of the end walls of the angle shaped frame.

The advantages of my improvements will be instantly understood and appreciated and 25 it will be seen that my improvements do not add appreciably to the cost of the cabinet; also that the improvements can be used upon floor or table sets with equal efficiency; also that the improvements may be applied 30 to cabinets in general use or to new cabinets; also that the improvements do not mar or detract from the beauty of the cabinet; also that a complete desk or smoker's set is provided, and that generally in every particular 35 the invention is useful, desirable, efficient and practical.

In the form of my invention shown in Figure 7, the structure provides both a smoker's appliance and a desk, and this form comprises the inner sliding leaf 23, the outer panel 24, hinged at 25, to swing upward when closed and said inner panel is guided in the cleats 26, and it will be apparent that this 40 form provides a most practical and efficient 45 smoker's appliance, and also provides a desk which is larger and more commodious than in the other form of my invention.

I claim:

1. A radio cabinet having a chamber, a 50 frame, means whereby the frame is mounted for movement into and out of said chamber, and a smoker's set carried by said frame and mounted in said frame to remain always in a vertical position when in and out of use, 55 said smoker's set, consisting of a member made from a single piece of flat material and comprising a horizontal platform and a pair of end vertical portions pivoted to said frame, and said platform being further provided with struck up clamps at one end thereof providing spring arms to engage suitable receptacles and with a central opening to form a seat for an ash receptacle.

2. A radio cabinet having a chamber, a 60 frame hinged with reference to said cham-

ber, a smoker's set, said smoker's set consisting of a member made from a single piece of flat material and comprising a horizontal platform and a pair of end vertical portions pivoted to said frame, and said platform being further provided with struck up clamps at one end thereof; providing spring arms to engage suitable receptacles and with a central opening to form a seat for an ash receptacle.

3. In combination with a cabinet having a chamber or compartment therein and transverse guides at each side of said compartment, a frame composed of a horizontal portion fitting and slidable in said guides and end walls secured to said horizontal portion, a front portion hinged at its lower edge to said horizontal portion to provide a closure and also to provide a desk when lowered and a smoker's set mounted upon the end walls of said frame.

In testimony whereof, I affix my signature.

LUTHER G. STUBBS.
